[57] CLAIM

The ornamental design for a "burial casket lid", as shown and described.

DESCRIPTION

FIG. 1 is a front elevational view of a "burial casket lid" showing my new design, the rear elevational view being identical thereto;

FIG. 2 is a top plan view thereof;

FIG. 3 is a right end elevational view thereof, the left end being identical thereto;

FIG. 4 is a bottom plan view thereof;

FIG. 5 is a front elevational view of a second embodiment of a burial casket lid showing my new design, the rear elevational view being identical;

FIG. 6 is a top plan view thereof;

FIG. 7 is a bottom plan view thereof;

FIG. 8 is a view taken in the direction of line 8—8 of FIG. 5; and,

FIG. 9 is a view taken in the direction of line 9—9 of FIG. 5.
